UNITED STATES PATENT OFFICE.

SAMUEL STRAUSS, OF LOS ANGELES, CALIFORNIA.

MACHINE FOR MAKING SHOES.

1,209,225.

Specification of Letters Patent.

Patented Dec. 19, 1916.

Application filed July 13, 1915. Serial No. 39,576.

To all whom it may concern:

Be it known that I, SAMUEL STRAUSS, a citizen of the United States, residing at Los Angeles, in the county of Los Angeles and 5 State of California, have invented a new and useful Machine for Making Shoes, of which the following is a specification.

An object of this invention is to maximize the ease of making shoes and to minimize the cost of production of the same.

Another object of this invention is to effect the manufacture of absolutely seamless one-piece shoes, thereby insuring comfort to the wearers thereof.

15 Another object is to provide a machine of this character which will effect the desired result in such a way as to make a shoe of the desired shape and style with a minimum number of operations.

20 Another object is to so mount the male die that it can be tipped at an angle to the female die so that the toe portion of the former can be inserted in and retracted from the latter.

25 Other objects and advantages may appear in the subjoined detail description.

The accompanying drawings illustrate the invention:

Figure 1 is a vertical mid section of a 30 machine built in accordance with this invention and capable of making the novel shoe, the operating parts being shown in their shoe-forming positions. Fig. 2 is a view analogous to Fig. 1, showing the male die retracted or thrown out of commission.

35 Fig. 3 is a vertical transverse section on irregular line indicated by x^3-x^3 , Fig. 1. Fig. 4 is a plan view partly in section on irregular line indicated by x^4-x^4 , Fig. 1.

40 Fig. 5 is a side view of the unfinished shoe produced by the machine shown in the preceding figures. Fig. 6 is a side view of the same shoe completed. Fig. 7 is a side view of the shoe shown in Fig. 6 with the addition of a supplementary sole. Fig. 8 is a

45 plan view of the shoe shown in Fig. 7.

There is provided a female die 1 of suitable material such as zinc or the like mounted in a base 2 provided with a mold cavity 3 having an undercut toe portion 4 adapted to receive a toe portion 5 of a male die which is formed of sections 6, 7, the section 6 being provided with the toe portion 5 and the section 7 forming the curved heel portion 5 that fits in the undercut heel portion 7'

of the female die. The die sections 6, 7 are provided with complementary inclined faces 8, 9 respectively adapted to seat against one another when the die 6, 7 is in the shoe-forming position shown in Fig. 1, 60 the section 7 being provided with a tongue 10 designed to engage a groove 11 in the face 8 of the section 6 so as to prevent the section 7 from sliding relative to said section 6 when the sections are inserted in the 65 die 1 and pressure is applied to said die sections.

The die sections 6, 7 are loosely and yieldingly connected to one another by a loose connection such as a coil spring 12 fastened 70 at its opposite ends to said sections respectively and designed to seat in recesses 12', 12" cut into the faces 8, 9 respectively.

The die 1 is provided with a top flat flange-forming face 13 having a groove 14 extending around the mouth of the cavity 3. Above the flat top face 13 of the die 1, there is provided a presser foot 15 having a bead 16 complementary to the groove 14, said presser foot being provided with perforations 17 to accommodate guide rods 18 mounted on the die 1 and projecting upward therefrom.

The presser foot 15 is provided with upwardly projecting ears 19 fastened by rivets 85 20 or equivalent to the lower ends of diagonally extending guide rods 21 on which is reciprocatively mounted a follower 22 having ears 23 provided with perforations 24 through which said rods 21 extend. The 90 follower 22 is pivoted at 25 to the upper ends of swinging arms 26 which are pivoted at 27 to a link 28 secured by a cap screw 29, or equivalent, to the die section 7. The follower 22 is normally supported, relative to 95 the presser foot 15 in the position shown in Fig. 2, by coil springs 30 surrounding the rods 21 between the ears 23 and abutments 31 projecting from the guide rods 21.

The male die 6, 7 and the parts moving 100 therewith may be operated by any suitable power and in the instance shown in the drawings said power may be applied through an arm 32 pivoted by the pivot 25 to the follower 22 between the upper ends of 105 the swinging arms 26. The presser foot 15 is provided with a rearwardly and upwardly inclined face 33 forming a rest and guide along which the male die slides when said die is moved up and down.

In practice to make the shoe shown at *a*, Fig. 6, the machine will be operated as follows: Assuming at the start that the parts are in the positions shown in Fig. 2, a piece 5 of leather 34 previously soaked in water will be placed on the flange-forming face 13 and the arm 32 will be operated to lower the presser foot 15 on to the leather to hold said leather in position. Then the lever 32 will 10 be operated still further to depress the follower 22 against the expansive force of the springs 30 to force the male die 6, 7 into the shoe-forming position as in Fig. 1, thereby pressing the leather into the desired shape 15 determined by the form of the dies so as to form the upper *b* and sole *c* all from the single piece of leather. Then the arm 32 will be operated to raise the follower 22 or allow said follower to be forced upward by 20 the expansive action of the springs 30, the first portion of said movement, owing to the sectional construction of the male die and to the loose connection between said sections, raising the section 7 and sliding said section forward relative to the section 6 so as 25 to withdraw the rear face of said section 7 out of the undercut heel portion 7', and further movement of the arm 32, by reason of the spring 12, withdrawing the toe section 6 from the undercut toe-forming portion 4 and at the same time raising the presser foot 15 out of engagement with the flange *d* of the shoe, so that the parts again assume 30 the positions shown in Fig. 2. To complete 35 the shoe formed as above, all that is necessary is to trim it by cutting off all or part of the flange *d* and, if desired, the upper may also be provided with a slit *e* of which the edges may be drawn toward one another 40 by laces or equivalents, not shown. Thus it is seen that the finished shoe is formed of a single piece of leather and is absolutely seamless.

If it is desired to have a shoe with a 45 heavier sole, a sole *f* may be fastened to the sole *c* as in Fig. 7.

I am not aware that a seamless shoe formed of a single piece of molded leather has even been known before this invention 50 thereof and the foregoing read in connection with the drawings filed herewith will enable those skilled in the art to which this invention pertains to make and use said invention.

I claim:

55 1. In a shoe machine, a female die provided with a cavity open only at its top and having an undercut toe-forming portion, a male die having a toe-forming portion, and means to move the male die downward into 60 the cavity and endwise to bring its toe-forming portion into the undercut portion of the cavity.

2. In a shoe machine, a female die provided with a cavity having an undercut toe-forming portion, a male die having a toe- 65

forming portion, a shiftably mounted follower, and a swinging connection between the male die and follower.

3. In a shoe machine, a female die provided with a cavity having an undercut toe- 70 forming portion, a male die having a toe-forming portion, a shiftably mounted follower, and an arm pivoted to the follower and pivoted to the male die.

4. In a shoe machine, a female die provided with a cavity having an undercut toe-forming portion and having a heel portion, a male die formed of separable toe and heel sections, and means to move the male die endwise so as to move the die sections into 80 and out of molding position.

5. In a shoe machine, a female die provided with a cavity having an undercut toe-forming portion and having an undercut heel-forming portion, a male die formed of 85 separable toe and heel sections designed to fit the toe and heel portions respectively of the female die, and means loosely connecting said die sections to one another to allow for independent movement of said die 90 sections.

6. In a shoe machine, a female die provided with a cavity having an undercut toe-forming portion and having a heel portion, and a male die formed of separable toe and heel sections having complementary beveled faces loosely engaging one another to allow 95 for independent movement of said die sections.

7. In a shoe machine, a female die provided with a cavity having an undercut toe-forming portion and having a heel portion, and a male die formed of separable toe and heel sections having complementary forwardly and upwardly inclined faces loosely 105 engaging one another to allow for relative movement of said die sections.

8. In a shoe machine, a female die provided with a cavity having an undercut toe-forming portion and having a heel portion, a male die formed of separable toe and heel sections having complementary forwardly and upwardly inclined faces, and means loosely connecting the sections together.

9. In a shoe machine, a female die provided with a cavity having an undercut toe-forming portion and having a heel portion, a male die formed of separable toe and heel sections, and a coil spring connecting said 115 sections to one another.

10. In a shoe machine, a female die provided with a cavity having an undercut toe-forming portion, a male die having a toe-forming portion, guide rods extending up from the female die, a member shiftably mounted on said guide rods, other guide rods fastened to said member and provided with abutments, a follower shiftably mounted on said other guide rods, springs surrounding said other guide rods between the 120 130

follower and said abutments, and an arm pivoted to the follower and to the male die.

11. In a shoe machine, a female die provided with a cavity having an undercut toe-forming portion, a male die having a toe-forming portion, guide rods extending up from the female die, a presser foot shiftably mounted on the guide rods to move toward and from the top face of the female die, 10 other guide rods fastened to said presser foot and provided with abutments, a follower shiftably mounted on said other guide rods, springs between the follower and said abutments, and an arm pivoted to the follower and to the male die.

12. In a shoe machine, a female die provided with a cavity having an undercut toe-forming portion, a male die having a toe-

forming portion, guide rods extending up from the female die, a presser foot shiftably mounted on the guide rods to move toward and from the top face of the female die, other guide rods extending aslant from the presser foot and provided with abutments, 20 a follower shiftably mounted on said other guide rods, springs between the follower and said abutments, and an arm pivoted to the follower and to the male die.

In testimony whereof, I have hereunto set my hand at Los Angeles, California, this 30 8th day of July, 1915.

SAMUEL STRAUSS.

In presence of—

GEORGE H. HILES,
A. F. SCHMIDTBAUER.
